United States Patent Office

Des. 225,040
Patented Oct. 31, 1972

225,040

Louis Marick, Grosse Pointe Farms, Mich., assignor to the United States of America as represented by the Secretary of the Army

Filed June 30, 1971, Ser. No. 158,669

Term of patent 14 years

Int. Cl. D12—15

U.S. Cl. D90—20

FIG. 1 is a perspective view of a tire showing my new design.

The tread is repeated as shown throughout the circumference of the tire and the side opposite to that shown is the same.

I claim:

The ornamental design for a tire, substantially as shown and described.
